Primary Examiner — Rhea Shields*Assistant Examiner* — Ikeadi M Ndukwu(74) *Attorney, Agent, or Firm* — Clement Cheng(57) **CLAIM**

The ornamental design for a battery case, as shown and described.

DESCRIPTION

FIG. 1 is a top front perspective view of a battery case showing my new design;

FIG. 2 is a bottom rear perspective view thereof;

FIG. 3 is a top plan elevation view thereof;

FIG. 4 is a front elevation view thereof, with the rear view being a mirror image thereof;

FIG. 5 is a right side elevation view thereof;

FIG. 6 is a left side elevation view thereof; and,

FIG. 7 is a bottom plan view thereof.

The broken lines shown in the drawings depict portions of the article that form no part of the claimed design.

1 Claim, 4 Drawing Sheets(56)
